UNITED STATES PATENT OFFICE.

GEORGE SYLVIN LOY, OF PARIS, FRANCE.

DESIGN FOR A TIRE-PRESSURE GAUGE.

Application filed May 14, 1927, Serial No. 21,974, and in France April 23, 1927: Term of patent 14 years.

To all whom it may concern:

Be it known that I, GEORGE SYLVIN LOY, a citizen of French Republic, residing at Paris, 24, rue de Liège, have invented a new, original, and ornamental Design for a Tire-Pressure Gauge, of which the following is a specification, reference being had to the accompanying drawing, forming part thereof.

Fig. 1 is a front view of the article, showing my new design.

Figs. 2 and 3 are a rear view and a side view of the same respectively.

What I claim is:

The ornamental design for a tire-pressure gauge, as shown.

In testimony whereof I have hereunto set my hand.

GEORGE SYLVIN LOY.
